Inventor
W. W. Wannamaker,

By Clarence O'Brien.

Attorney

UNITED STATES PATENT OFFICE.

WILLIAM W. WANNAMAKER, JR., OF ORANGEBURG, SOUTH CAROLINA.

PILE-HEAD PROTECTOR.

Application filed March 9, 1926. Serial No. 93,458.

The present invention relates to a pile head protector, and has for its object to provide a cheap, convenient, and durable means for protecting the heads of wooden piles from moisture and unequal bearing and other factors which tend to cause decay, at, near or through the head.

With the above and numerous other objects in view as will appear as the description proceeds, the invention resides in certain novel features of construction and arrangement of parts as will be hereinafter more fully described and claimed.

In the drawing:—

15 Figure 1 is a fragmentary view showing a cap supported by two piles having my improved pile head protector thereon,

Fig. 2 is a bottom plan view of the non-elastic portion of my improved pile protector, and

Fig. 3 is a sectional view through my improved pile protector.

Referring to the drawing in detail, it will be seen that the letters P denote piles for supporting the cap C. The letters D denote the drift pins. My improved pile head protectors are designated generally by the letters A. Referring particularly to one of the protectors, it will be seen that the numeral 5 designates the top plate of a non-elastic shield having a frusto-conical marginal flange 6 depending therefrom. The numeral 7 denotes the inner cushion of elastic material which is caused to adhere to the bottom surface of the shield or outer casing by a coating of bituminous material 8. The outer casing or shield is made of pressed metal, especially galvanized iron, although it may be made of any metal or combinations of metals painted or not, as may be desired.

This outer casing is shaped roughly like an inverted pie plate. The smaller inside diameter is equal or greater than that of the pile it protects. A number of various sizes is used so that any size pile may be capped without protruding excessively. The purpose of the outer casing or shield is to prevent moisture from reaching the cushion 7 and the pile head properly, because moisture which gets into the cracks and pores in the head accelerates decay.

The inner cushion 7 is made up of one or more circular layers of tar paper or other

similar material. This cushion is stuck to the inside of the outer casing by pitch, asphaltic cement, or other suitable cementing material. The cushion being stuck to the casing as a unit, allows the protector to be more easily handled and installed, and also tends to preserve the cushion. The purpose of the inner cushion is to distribute the load over minor irregularities in the pile head proper, and also to assist in rendering the pile head proper moisture-proof.

65 The manner of using the pile head protector is as follows:—

After the pile is driven in place and sawed off ready to be capped, it is covered with the pile protector. The cap C is then 70 put in place. A hole for the drift pins D is then bored through the cap, but not through the protector as that might injure the bit or drill. The drift pin is then driven through the hole in the cap, through 75 the protector, and into the pile as usual. Before placing the protector on a treated pile, the head should be treated with the same preservative used in the treatment of the pile. For instance, a creosoted pile 80 should be treated with an application of hot creosote followed by tar or pitch before placing the protector thereon. This treatment will make a better joint, and is desirable but not necessary, in order to make 85 profitable use of the protector.

The present embodiment of the invention has been disclosed in detail since in actual practice it attains the features of advantage enumerated as desirable in the statement of 90 the invention and the above description.

It will be apparent, however, that changes in the details of construction, in the materials, and in the combination and arrangement of parts may be resorted to without departing from the spirit or scope of the invention as hereinafter claimed or sacrificing any of its advantages.

Having thus described my invention, what I claim as new is:—

100 A pile head protector including an outer casing of metal comprising a circular body having a marginal depending frusto-conical flange, and an elastic cushion within the casing and cemented thereto.

105 In testimony whereof I affix my signature.

WILLIAM W. WANNAMAKER, JR.
